COMBINED SOAP DISH AND SHELF

Hans J. Kunz, 257 Village Lane,
Grand Junction, Colo. 81501

Filed Aug. 5, 1966, Ser. No. 3,364

Term of patent 14 years

(Cl. D4—3)

FIG. 1 is a perspective view of a combined soap dish and shelf, showing my new design.

FIG. 2 is an elevational end view thereof, the opposite end being identical.

FIG. 3 is a top view, and

FIG. 4 is an elevational front view thereof.

The fragmentary broken line representation of a wall in FIGS. 1 and 2 is for purposes of illustration only.

I claim:

The ornamental design for a combined soap dish and shelf, substantially as shown and described.
